AUGER SHAFT

Hilmar E. Satre, Chicago, Ill., assignor, by mesne assignments, to First Caisson Machinery & Boring Co., Chicago, Ill., a corporation of Illinois

Application May 5, 1934, Serial No. 724,130
Renewed December 11, 1937

3 Claims. (Cl. 255—28)

This invention pertains to boring apparatus and has particular reference to the lead and operating shaft for rotating the boring auger and guiding the same vertically in its operation and 5 also in its ascent to dumping position and its descent to operating position; more especially the invention relates to the provision therein for adjustability as to length to accommodate the gradually deepening bore of the hole being excavated.

With these objects in view I provide a sectional shaft, the sections readily coupled together and firmly held in assembled relation, said shaft sections provided with aligned ribs or 15 grooves for cooperation with a corresponding groove or rib carried by the auger bucket, forming a splined coupling to provide a positive connection against relative angular movement whereby to rotate the auger with the shaft while 20 permitting of free sliding movement of the auger on the shaft in its ascent and descent.

In order to facilitate an understanding of the invention a preferred embodiment of the same is set forth in the following detailed description 25 predicated upon the accompanying drawings, wherein—

Fig. 1 is a sectional view through a boring auger in assembled relation to the driving and guiding shaft;

Fig. 2 is a side elevation partly in section showing adjacent ends of shaft sections when separated;

Fig. 3 is a medial longitudinal section through adjacent ends of the shaft section assembled;

Fig. 4 is a transverse section on the line 4—4 of Fig. 2;

Fig. 5 is a top plan view of a shaft section on the line 5—5 of Fig. 2;

Fig. 6 is a transverse section through the shaft intermediate the joints;

Fig. 7 is a side elevation of the shaft shown in Figs. 1 to 6;

Fig. 8 is an enlarged view, broken, showing in side elevation and section means for coupling the sections and attaching the guiding ribs;

Fig. 9 is a side elevation of the upper coupling section slightly modified from that shown in Fig. 7;

Fig. 10 is a transverse section on the line 10—10 of Fig. 9 with the coupling bolts omitted; and

Fig. 11 is a side elevation of Fig. 10 broken away to show the coupling bolts in place.

This application is a continuation in part of my copending application Serial No. 517,845, now

Patent No. 1,998,591, granted April 23, 1935, under a requirement for division.

The structure of the auger bucket 11 forms no essential part of the present invention but is of the rotary type with bottom cutters 12 whereby the excavated material is fed into the bucket interior for hoisting and dumping at intervals. The bucket is here shown for the purpose of facilitating an understanding of the relation of such a bucket to the lead shaft which forms the 10 subject matter of the present application.

The lead shaft as shown in this case comprises a plurality of sections 13 having longitudinally extending ribs 14 and the lowermost section provided with a boring bit 15 which serves to feed 15 the shaft downwardly under its own weight and to serve as an anchorage for the bottom of the shaft to prevent lateral displacement.

The upper end of each shaft section is cored out to form a cavity 16 marginally surrounded by a turreted construction, alternating projections 17 and intermediate notches 18. The lower end of each section, other than the lowermost provided with the bit 15, presents a complementary structure with projections 17 and intermediate notches 18 for interfitting with the corresponding turreted upper end of the next lower section and is likewise cored out to form a cavity 16. A plug member 19 is arranged to fit within each of the cavities 16 of the adjacent 20 shaft sections and is apertured at 20 to register with corresponding apertures 21 in the shaft section whereby coupling bolts 22 may be placed in the apertures and thus transfix and rigidly connect the two shaft sections with the coupling plug.

These connecting bolts may be plain and driven into place after the manner of rivets as shown in Figs. 3 and 4, having their outer ends flush with the outer edge of the ribs 14 and may be 40 provided with set screws 23 as a further safeguard against loosening; or, as shown in Fig. 6, the ribs 14 may be connected with the plug 19 by lag bolts 24 extending through the ribs and the shell 13 of the shaft into the plug 19. 45

The plug 19 of the uppermost section has connected therewith a coupling member 25 swiveled thereto by means of which a cable 26 is attached. This swivel connection permits the shaft to be rotated for facilitating its own progress downwardly and also for operating the auger, as set forth for instance in my copending application above referred to, without twisting the cable 26. 50

As shown in Fig. 8, the plug 19 may be connected with the hollowed end portions 16 of the 55

shaft 13 by threaded bolts 27, the heads of which as well as the nuts 28 and lock washers 28a are seated within recesses 29 of the ribs 14.

Having reference to Figs. 9, 10 and 11, the 5 ribs are omitted and instead grooves 30 are provided within which corresponding projections on the auger bucket slide and interlock against angular movement. The coupling connection between the plug 19 and the adjacent shaft ends 10 are similar to that previously described with reference to Figs. 1 to 8 but in this case the apertures 20 are preferably arranged at right angles to the grooves 30 and transfixing bolts 31 disposed within the sleeves 32 are employed similar 15 to the connecting bolts in Fig. 8 save that the nuts 28 and the washers 28a are accommodated within recesses 33 in the wall of the shaft 13.

It is to be observed that the ribs 14 are not an integral part of the shaft 13 but are seated in 20 grooves formed in the shaft and removable for replacement. The wear, as the bucket slides on the shaft, is primarily and almost exclusively on the ribs rather than the shaft body, and as the results of wear become serious the ribs only need 25 be replaced instead of installing a new shaft at great expense. Moreover the ribs within the grooves constitute a very efficient reinforcement of the shaft against flexure.

I claim:

- 30 1. A sectional auger guiding and driving shaft for a machine of the character described, comprising a plurality of shaft sections having their circumferential surface interrupted by oppositely disposed longitudinally extending guiding ribs, 35 the shaft sections hollowed at their adjacent ends with their terminal edges provided with interfitting projections and notches whereby to prevent relative rotation of the adjacent shaft sections and to align the ribs, a plug member arranged within the hollow portions of the shaft sections to bridge the interfitting projections,

and securing elements extending transversely of the plug member and the shaft sections and into the ribs, the ribs being replaceable.

2. A sectional auger guiding and driving shaft 5 for a machine of the character described, comprising a plurality of shaft sections having their circumferential surface interrupted by oppositely disposed longitudinally extending grooves, guiding ribs removably secured within the grooves, the shaft sections hollowed at their adjacent 10 ends with their terminal edges provided with interfitting projections and notches whereby to prevent relative rotation of the adjacent shaft sections and to align the grooves, a plug member arranged within the hollow portions of the shaft 15 sections to bridge the interfitting projections, and securing elements extending transversely of the plug member and the shaft sections, said securing elements anchored at their ends to prevent shifting.

3. The combination with an excavating auger bucket, of means for guiding and rotating said bucket and compensating for downward progress comprising a sectional shaft having at its lower end a guiding bit and at its upper end a swivel 25 connection for a suspending cable, said sectional guiding and driving shaft consisting of a plurality of units hollow at their adjacent ends and with their ends turreted to provide interfitting 30 projections and notches having side walls, and a joining plug member arranged within the hollow portions of the shaft sections and bridging the joint between adjacent sections, with bolts extending transversely of the plug members and shaft sections, the shaft being grooved and provided with reinforcing driving means comprising ribs seated within the grooves and removably anchored therein by the said bolts and by other bolts intermediate the length of the shaft units.

HILMAR E. SATRE.
